UNITED STATES PATENT OFFICE.

SOLOMON D. ROGERS, OF SACRAMENTO, CALIFORNIA, ASSIGNOR TO COMMERCIAL CARS CONSTRUCTION CO., OF SAN FRANCISCO, CALIFORNIA, A CORPORATION OF CALIFORNIA.

RAILROAD-CAR.

1,350,567.

Specification of Letters Patent. Patented Aug. 24, 1920.

Application filed November 15, 1916. Serial No. 131,365.

To all whom it may concern:

Be it known that I, SOLOMON D. ROGERS, a citizen of the United States, residing at Sacramento, in the county of Sacramento and State of California, have invented new and useful Improvements in Railroad-Cars, of which the following is a specification.

Principal items in the expense of running interurban railroad cars have heretofore been, first, the great weight of the car supposed to be necessary to give tractive power, second, the construction and maintenance of the heavy road bed which is required to withstand the great momentum of the heavy car, and third, the trolleys and wires.

The object of the present invention is to provide a railroad car, first, having great tractive power but of comparatively light weight, thereby also reducing the initial cost and cost of maintenance of the road, second, which can be quickly started and stopped, third, so constructed that the driving mechanism can readily be removed from under the body of the car and another substituted therefor, and, fourth, dispensing with the necessity for using wires and trolleys.

In the accompanying drawings, Figure 1 is a side view of my improved motor car; Fig. 2 is a horizontal section thereof; Fig. 3 is an enlarged side view of a driven truck and the engine for driving the same, the floor of the car being shown in vertical section; Fig. 4 is a plan view of the same; Fig. 5 is a cross section of the same on the line 5—5 of Fig. 4; Fig. 6 is an enlarged vertical section on the line 6—6 of Fig. 4.

Referring to the drawing, 1 indicates the body of a car supported upon a front truck 2 and a rear truck 3. Said body is supported on the front truck 2 by means of carriage springs 4, the ends of which are suitably connected to blocks 6 bolted to beams 7 on the under side of the floor 8 of the car. The middles of said springs are clamped by clamps 9 to the ends of an arched hanger 11, the middle of which is pivotally connected by a king bolt 12 to the middle of an arched support 13, the ends of which are secured to circular wearing plates 14, which plates and reinforcing blocks 15 within and next to the plates are bolted, as shown at 16,

to channel-irons 17, the ends of which are secured by U-bolts 18 to the axle casings 19 of the forward truck.

The axles 20 in said casings are, as shown, differential axles, and the worms 21 for driving the axles 20 are placed beneath the worm gears 22 on the axles and connected by universal joints 23 to a shaft 24 driven by means of an involute toothed gear 25 on a portion thereof near the front driving axle, around which is a silent chain 26 which passes around an involute toothed gear 27 on the front end of a driving shaft 28, driven by a gasoline engine 29. The fly wheel casing 30 of said engine is bolted to one end of the transmission case 31, through the other end of which extends the shaft 32, the transmission having the usual shifting lever 33 and brake lever 34.

The wheels on both the front and rear axles of the truck are provided with flanges 35 to engage the inner sides of the wheels, and have on their inner sides braking drums 36, concentric with said axles.

The car is supported upon two trucks, a driving truck at the front end and a trailer truck at the rear end, both pivotally connected to the body of the car.

The interior of the car is divided into an engine room 41 at the front, a baggage room 42 at the rear of the engine room, a smoking room 43 behind the baggage room, two entrance vestibules 44, one on each side of the car, and a lavatory 46 at the middle of the car between the vestibules behind the baggage room and a parlor 47 behind the vestibules and lavatory, there being also an observation platform 48 behind the parlor compartment.

In the parlor I have adopted what I believe to be a novel seating plan. The seats 49 are arranged in two longitudinal rows at the sides of the parlor. Each seat is permanently fixed to the floor, so as to extend in a forward direction making an angle of 60° with the longitudinal direction of the car.

The main seat 51 in the smoking room is at the front thereof next to the baggage room, and the floors 52, 53 of the baggage room and the main portion of the engine room are higher than the remainder of the floor 54 of the car and level with said main

seat, but portions 55 of the floor of the engine and baggage rooms over the engine, are raised, the raised portion immediately behind the controlling levers, which extend 5 upwardly through holes 56, 57 in the floor of the engine room, forming a seat 58 for the driver of the engine convenient for operating said controlling levers.

The walls of the car converge at its front 10 end 59, and since the front wheels of the truck are located at the extreme front end of the car, housings 60 for the upper portion of said wheels are erected upon the supports for the frame of the car. Skirtings 61 for 15 the wheels of the front truck also depend from said supports and protect them against dirt and also act as safety devices.

The following are some of the advantages of my improved construction:

20 My improved car possesses great tractive power in proportion to its weight, owing to the fact that both the front and rear wheels of the driving truck are positively driven. The use of an internal combustion engine 25 for the motive power permits it to be quickly started and stopped. The front of the body of the car can be easily disengaged and raised from the driving truck, thereby permitting another driving truck to be 30 quickly substituted if desired for repair. The connection between the engine and the driving axles by means of a worm and worm gear, and especially the location of the worms on the under sides of the driving 35 axles, instead of above the same, as in general automobile construction, permits of the engine being placed low down and the floor of the engine room and baggage room to be but little above the remainder of the floor of 40 the car. The provision of universal joints between the ends of the driving shaft and the worm shafts avoids the strain upon the driving shaft due to inequalities of the road bed or unevenness of the rail. The location 45 of the transmission mechanism in front of the engine, instead of behind the same, as is general automobile practice, permits of the engine being concealed beneath the engine and baggage rooms and allows the driver of 50 the engine to control the engine from an extreme front portion of the car, where objects on or near the track in front of the car are plainly visible.

The arrangement of the floor by which a 55 portion of the floor of the engine and baggage rooms is above the engine, and the remaining portion is below the engine shaft, permits of the main portion of the floor, supporting the passengers, to be comparatively 60 low. The arrangement by which a portion of the floor, immediately above the fifth wheel of the driving truck, is still further raised, permits of the latter being used as a seat for the driver of the engine. The use 65 of differential axles on the driving truck of

a car avoids strain upon the truck due to unevenness of the rails. The use of a driving wheel adapted to run upon a rail and at the same time having a braking drum on its inner side permits of the usual braking mechanism for braking automobiles being applied to a railroad car. The arrangement of the seats in longitudinally extending rows, each seat being fixed to the floor of the car and directed forwardly and inwardly, 70 permits of accommodating passengers in the greatest number and with the most comfort to themselves. The form of the front of the car, namely, that the walls converge toward the front, and that it has housings for 80 its wheels, reduces the resistance of the air to the motion of the car.

I claim:—

1. A motor car comprising a body, a truck for supporting the body, a motor supported on said truck, and an operative connection between said motor and a wheel axle of the truck, comprising the motor shaft, a worm operatively connected to said motor shaft and below the wheel axles of the truck, 85 and a worm gear on one of said wheel axles meshing with said worm.

2. A motor car comprising a body, a truck for supporting the body, a motor supported on said truck, and an operative connection 95 between said motor and the wheel axles of the truck, comprising a motor shaft, a driving shaft operatively connected to said motor shaft, worms on the ends of said driving shaft and below the wheel axles of the 100 truck, and worm gears on said wheel axles meshing with said worms.

3. A motor car comprising a body, a truck for supporting the body, a motor supported on said truck, and an operative connection 105 between said motor and the wheel axles of the truck, comprising a motor shaft, a driving shaft operatively connected to said motor shaft, worms on the ends of said driving shaft and below the wheel axles of the 110 truck, universal joints interposed between the driving shaft and the worms, and worm gears on said wheel axles meshing with said worms.

4. A motor car comprising a truck, a 115 motor supported on said truck and operatively connected with one of the axles of the truck, and a car body, the main portion of the floor of which is below the shaft of the engine, but a portion of which floor is raised 120 above the main portion of the engine.

5. A motor car comprising a truck, a motor supported on said truck and operatively connected with one of the axles of the truck, and a car body, the main portion of the floor of which is below the shaft of the engine, but a portion of which floor is raised 125 above the main portion of the engine, a portion of the latter immediately over the fifth wheel of the driving truck being raised.

6. A motor car comprising a truck, a motor supported on said truck and operatively connected with one of the axles of the truck, and a car body, the main portion 5 of the floor of which is below the shaft of the engine, but a portion of which floor is raised above the main portion of the engine, a portion of the latter having an opening therethrough to permit the controlling

mechanism to project upwardly above said 10 portion.

In testimony whereof I have hereunto set my hand in the presence of two subscribing witnesses.

SOLOMON D. ROGERS.
